UNITED STATES PATENT OFFICE.

WILLIAM STEWART, OF NEWARK, NEW JERSEY.

LIFEBOAT.

1,420,459.

Specification of Letters Patent. Patented June 20, 1922.

Application filed September 21, 1921. Serial No. 502,192.

To all whom it may concern:

Be it known that I, WILLIAM STEWART, a citizen of the United States, and a resident of Newark, in the county of Essex and State 5 of New Jersey, have invented a new and Improved Lifeboat, of which the following is a full, clear, and exact description.

This invention has relation and refers particularly to an improvement in life boats, 10 the same having as one of its principal objects to produce a boat which may be properly nested with others of the same kind, whereby a number of such boats when nested will occupy a minimum amount of deck 15 space on a vessel, and whereby a single pair of davits may be conveniently utilized to effect the launching of each of said nested boats singly.

As a further object the invention seeks to 20 provide a strong, durable and efficient life boat, the construction of which renders the same more sea-worthy and less liable to capsize or over-turn.

As a still further object the invention contemplates a life boat provided with removable buoyant elements and cross seats, the latter capable of being removed and stored in the bottom of the boat to permit of the nesting of a number of said boats one within 30 the other and whereby the buoyant members may be removed for the purpose of repairs or renewal when damaged.

As a more specific object the invention contemplates means for securing the removable seats in place, which means also serve as lateral bracing elements for the boat.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the 45 full extent indicated by the general meaning of the terms in which the claims are expressed and by variations in the phraseology of the same.

In the drawings—

50 Figure 1 is a side elevation illustrating a number of life boats constructed in accordance with the invention in nested relation.

Fig. 2 is a plan view of one of the boats, illustrating one of the cross seats removed 55 and stored in the bottom.

Fig. 3 is a longitudinal sectional view

therethrough taken on the line indicated at 3—3 in Fig. 2.

Fig. 4 is a transverse sectional view of one of the life boats and illustrating in dotted lines other boats in nested relation thereto.

Referring to the drawings by characters of reference, the hull consists of a bottom 10 and side walls 11, the side walls including upper and lower sections 12 and 13 which 15 diverge with respect to each other from their lower ends to their upper ends. The upper and lower side wall sections are joined by horizontal steps 14 which respectively connect the lower edge of each upper side wall 20 section 12 with the upper edge of each lower side wall section 13 and provide within the hull interior shelves 15 extending fore and aft. The side wall sections 12 and 13 merge into one another at the ends of the hull and 25 are connected to the stem posts 16 of the keel 17. The opposite extremities of the steps and shelves 14 and 15 converge and vanish at the stem posts. The upper edges 30 of the upper side wall sections 12 are formed with the usual gunwale 18 supporting the oar-locks 19 in spaced relation. Longitudinally extending seats 20 are supported within the hull in superposed relation to the shelves 15 to afford therebetween a receiving 35 space for a plurality of buoyant elements 21 in the nature of sealed watertight tanks or the equivalent thereof. The longitudinal seats 20 are preferably supported by vertical stepped braces 22. The buoyant elements or sealed tanks 21 are arranged longitudinally of the hull and disposed between the shelves 15 and the longitudinal seats 20, with their end walls spaced from each other. The buoyant elements are removable or 40 portable whereby the same may be disassociated from the hull for the purpose of repairs or renewal when damaged or otherwise rendered unfit or unsafe for use. In addition to the longitudinal seats 20 which are stationary, a 45 plurality of detachable transverse seats 23 are employed, the same being adapted to be supported from the longitudinal seats. Each of the transverse seats is provided adjacent its opposite extremity with an eye 50 bolt 24 extending therethrough with the shanks 25 depending therefrom for insertion within the apertures 26 in the longitudinal seats, said apertures being disposed therein to register with the spaces between the ends 55 of the buoyant elements 21. A hook 27 is carried by the upper end of each eye bolt

and the bill 28 thereof is designed to engage with a keeper 29 on the inside of the upper side section adjacent the gunwale. By this arrangement it will be seen that when the transverse seats are arranged in place the shanks 25 will be received by the apertures 26 to properly position the transverse seats, and the hooks when engaged with the keepers will prevent casual or accidental displacement of the transverse seats, while at the same time serving as lateral braces for the side walls to prevent the spreading or relative separation of the same. When it is desired to nest a plurality of boats, the transverse seats are removed and the longitudinal seats 20 of a lower boat will coact with the steps 14 of the next adjacent upper boat to support said upper boat and provide a storage space between the bottoms of said nested boats for the transverse seats, or masts or other articles constituting the equipment for the same. In addition to the longitudinal seats 20, combination longitudinal seats and foot rests 30 are supported from the bottom 10 of the hull by the supporting brackets 31 whereby occupants seated on the seats 20 may rest their feet on the combination seats and foot rests 30, permitting other occupants to sit between the feet of the occupants on the longitudinal seats 20 whereby to afford a maximum seating capacity. The combination longitudinal seats and foot rests 30 terminate an appreciable distance from each end of the hull and within the space thus provided storage tanks 32 are arranged for water and food supply. One of the transverse seats 23 is provided with a mast receiving eye 33 which affords means for stepping the mast.

The formation of the hull provides the side walls with stepped portions which coact with the water to render the boat more stable and seaworthy in a heavy sea, to minimize the possibility of capsizing, while at the same time materially adding to and strengthening the structure due to the fact that the horizontal steps act as lateral stiffening means for the hull. By this arrangement it will be seen that a number of boats of this construction may be nested to occupy a minimum amount of deck space and each nested set will require but a single pair of davits to effect the launching. Furthermore the construction of the hull eliminates the necessity of employing expensive chocks or cradles as two skids will be sufficient to support a complete set of nested boats by positioning the same beneath the stepped portions of the sides.

60 Claims:

1. In a life boat, a hull comprising a bottom and laterally stepped side walls including upper and lower divergent sections connected by a horizontal step extending fore

and aft, said steps within the hull constituting shelves, longitudinal seats superposed with respect thereto affording a receiving space therebetween, removable buoyant elements interposed between the shelves and longitudinal seats, transverse seats adapted to be supported by the longitudinal shelves, and means for detachably associating said transverse seats with the longitudinal seats. 65

2. In a life boat, a hull comprising a bottom and laterally stepped side walls including upper and lower divergent sections connected by a horizontal step extending fore and aft, said steps within the hull constituting shelves, longitudinal seats superposed with respect thereto affording a receiving 75 space therebetween, removable buoyant elements interposed between the shelves and longitudinal seats, transverse seats adapted to be supported by the longitudinal shelves, and means for detachably associating said transverse seats with the longitudinal seats, 80 said means adapted to coact with the upper side wall sections to brace the same longitudinally. 85

3. In a life boat construction, a hull including a bottom wall having a keel provided with upstanding stem posts at its opposite ends, and side walls comprising upper and lower divergent sections and a horizontal step connecting the lower edge of each upper section and the upper edge of each lower section, said side wall sections connected at their opposite extremity with the stem posts and merging into each other at their point of connection with the stem 90 posts, said horizontal steps forming the interior of the hull with longitudinal shelves, longitudinally arranged seats superposed with respect to said shelves adapted to coact with the steps of a boat of like construction when nested therewith to space the bottom of said second boat from the bottom 95 of the first boat to afford a storage space for the transverse seats and other equipment. 100

4. In a life boat construction, a hull including a bottom and stepped side walls providing an upper portion of greater area than the lower portion, longitudinal seats superposed with respect to the inner stepped portions of the sides, transverse seats adapted to 115 be supported by the longitudinal seats and detachably associated therewith whereby upon nesting of two or more of said boats, the longitudinal seats will coact with the stepped portions of the upper adjacent boat 120 to provide a receiving space between the bottoms of said nested boats for the reception of the transverse seats and other equipment, and whereby the exterior stepped portions of the hull will coact with the water to minimize the rolling of the boats in a heavy sea. 125
